UNITED STATES PATENT OFFICE.

CHARLES A. CLARK, OF HARTFORD, CONNECTICUT, ASSIGNOR TO TRUMBULL ELECTRIC MANUFACTURING COMPANY, OF PLAINVILLE, CONNECTICUT, A CORPORATION OF CONNECTICUT.

PUSH-BUTTON SWITCH.

1,033,152.

Specification of Letters Patent. Patented July 23, 1912.

Application filed November 23, 1909. Serial No. 529,541.

To all whom it may concern:

Be it known that I, CHARLES A. CLARK, a citizen of the United States, and a resident of Hartford, in the county of Hartford and State of Connecticut, have invented certain new and useful Improvements in Push-Button Switches, of which the following is a full, clear, and exact description, whereby any one skilled in the art may make and use 10 the same.

The invention relates to electric switches and more particularly switches of the type known as push button switches, wherein a movable contact bar actuated by a pair of 15 push buttons makes and breaks the circuit between stationary contact members, the whole mechanism being arranged in a suitable receptacle.

The object of the invention is to simplify, 20 as far as possible, the mechanism of such a device and condense it in size to the smallest limits commensurate with proper operation of the parts and control of the circuit.

A still further object is to eliminate the 25 complicated locking mechanisms employed in various types of push button switches for locking and releasing the switch bar.

A still further object is to provide a device in which the various parts may be most 30 cheaply and economically formed of sheet metal by stamping or pressing them to form.

Referring to the drawings:—Figure 1 is a detail sectional view through a receptacle, 35 illustrating the switch mechanism. Fig. 2 is a plan view of the mechanism shown in Fig. 1. Fig. 3 is a partial sectional view through the mechanism along the line of the supporting spindle. Fig. 4 is a view of the parts looking from the opposite side of the 40 mechanism as illustrated in Fig. 1. Fig. 5 is a perspective view illustrating the several parts of the mechanism unassembled. In this figure, 5^a indicates the actuator plate with its push buttons; 5^b indicates the contact plate or bar; 5^c illustrates the locking plate of the switch bar; 5^d illustrates the tension spring and washers appurtenant thereto; 5^e illustrates the trigger or stop for holding the locking plate with its pivot and 45 spring; 5^f illustrates the supporting plate of the several parts of the mechanism. Fig. 6

is a plan view of the plate illustrated at 5^f, showing the stamping from which said plate 5^f is formed.

In the accompanying drawings, the 55 numeral 1, denotes a receptacle of suitable insulating material within which the several parts are mounted. Secured within said receptacle is a switch plate or support 2, which, as illustrated in Fig. 6 and 5^f, Fig. 5, 60 of the drawings, is stamped out of sheet metal and struck up to form the support for the various movable parts of the switch mechanism. Suitably mounted in the receptacle are stationary contacts 3, 3^a, which 65 are provided with suitable connections and form the terminals of the circuit to be controlled by the switch. At one side of the supporting plate 2, is arranged a switch bar 4, suitably secured to a locking plate 5, 70 through insulating bushings 6. This plate 5, has a member 7, projecting over the upper edge of the supporting plate 2, and is secured to a spindle 8, which passes through a spindle opening 9, arranged adjacent to 75 the upper edge of the plate 2. At the lower side of the locking plate 5, is an inturned lug 10, which cooperates with a latch or trigger as hereinafter described.

On the opposite side of the supporting 80 plate 2, from that occupied by the locking plate 5, and its contact bar 4, is an actuating plate 11, provided with a central tubular bearing 12, adapted to engage the stud 8, 85 where it projects through the plate 2. The several parts are held in place by a washer 13, and nut 14. At either end of the bar 11, are pivotally arranged the push buttons 15, 16, a depression of either one of which rocks the plate 11, upon its pivot bearing 8. The 90 upper edge of the plate 11, has a projecting lug 17, which underlies the lug 7, of the locking plate. A coil-spring 18, having upwardly extending arms 19, and 20, is arranged upon the tubular bearing 12, with 95 its arms 19, and 20, projecting on opposite sides of the two lugs 7, and 17.

The plate 2, is of somewhat peculiar construction, being stamped or blanked out of sheet metal and provided at its upper edge 100 with an opening 21, formed substantially concentric with the pivot opening 9, and

having abrupt shoulders 22, 23, which serve as stops for limiting the movement of the lug 7, borne upon the locking plate 5. The lower portion of the plate is turned up as at 5 24, to provide a support for a pivotal bearing 25, for a latch or trigger 26, which is normally held in raised position by the spring 27, encircling the pivot 25, and has its forward end 28, projecting through slot 10 29, in the plate 2, in position to engage either one side or the other of the lug 10, of the locking plate 5. When the parts are in normal position, the two projections 7, and 15 17, are in registering position one with the other, and the lug 10, of the locking plate 5, rests at one side of the end 28, of the trigger 26, while the projections 7, and 17, of the plates 5, and 11, rest against one of the shoulders 22 or 23. Obviously, with the 20 parts in this position, the switch blade 4, is securely locked against movement, as the plate 5, through its projection 7, and locking lug 10, is firmly held between the latch 26, and one of the abrupt shoulders of the plate 2.

25 Upon a movement of the actuating plate 11, by depression of one of the push buttons, the projection 17, will be moved away from the projection 7, and by this movement, the spring 18, will be fully tensioned, 30 owing to the fact that the plate 5, is still securely held by the latch 26. Upon a final movement of the plate 11, its lower edge will come into contact with the upper side of the latch 26, depressing said latch until its 35 end is depressed sufficiently to release the locking plate 5. Thereupon, said plate will be partially rotated with the switch bar 4, by a very rapid movement, until the projection 7, strikes against one of the shoulders 40 of the supporting plate. Then the latch 26, will engage the opposite side of the locking lug 10, and hold the parts locked in the new position, the plate 5, being held against movement by the engagement of its projection 7, with the locking shoulders of the 45 plate 2, and the engagement of the locking lug 10, with the trigger 26. It will be observed in this construction that there is no oscillating member or cam movement for 50 controlling the release and locking of the contact bar and its plate and that by having the trigger mounted at one side of the supporting plate and passing under the actuating plate 11 mounted on one side of the plate 55 and extending into position to engage the locking plate mounted upon the opposite side of the supporting plate 2, that the whole structure may be condensed into comparatively small proportions and yet will form 60 an effective device, having a very simple mechanism.

All of the several parts, as illustrated in Figs. 5 and 6 may be pressed up or stamped from sheet metal, and when assembled, give 65 an extremely durable and efficient device,

occupying but very small space. It has all the advantages of a positive lock for the switch bar either in its open or closed circuit relation with the terminals 1, and 2, and there is no opportunity for said bar to jar loose. It is important that the actuating bar 11, shall be fully depressed and the spring 18, fully tensioned before the locking plate 5, can be released, as the lower edge of the actuating bar 11, comes in contact with the trigger 26, only upon final depression of the former. 75

Obviously, various changes might be made in the exact details of the construction described without departing from the spirit or intent of the invention, and the device is 80 equally applicable to both single and double pole switches.

What I claim as my invention and desire to secure by Letters Patent is:—

1. In a push button switch, a supporting plate, an oscillatory plate provided with a locking lug, a contact bar movable with the oscillatory plate, a pivoted actuating plate movable relatively to the supporting plate, a pivoted trigger mounted at one side of the pivot about which the actuating plate moves and extending through the supporting plate to engage with the locking lug of the actuating plate, the lower edge of the actuating plate being arranged to engage with the trigger only near the limit of its movement, in order to disengage it from the said locking lug, and a spring for holding the trigger in position to engage the locking lug. 95

2. In a push button switch, a supporting plate, an oscillatory locking plate pivotally mounted therein, and provided with a projection extending over the locking plate, an actuating plate concentrically mounted with reference to the locking plate and having a projecting lug registering with the lug of the locking plate, shoulders formed upon the supporting plate for limiting the movement of the locking and actuating plates, a trigger 100 pivoted to the supporting plate and extending therethrough, said trigger adapted to engage and lock the locking plate on one side of said plate and with a portion adapted to be engaged by the lower edge of the actuating plate on the opposite side of the supporting plate, a spring acting upon the trigger for moving it into engagement with the locking plate and means for tensioning the locking plate while it is held by the 105 trigger. 115

3. In a push button switch, a supporting plate having stop shoulders on its upper edge, a pivot opening adjacent thereto, a locking plate having a pivot passing therethrough, said plate provided with a projection extending between the locking shoulders of the supporting plate, an actuating plate pivotally mounted upon the pivot of the locking plate and provided with a projection 120

normally registering with the projecting lug | said plate by the actuating plate, and means of said locking plate, resilient means connecting said projections, a trigger pivotally mounted on the base of the supporting plate | for moving said actuating plate.

5 and projecting through said plate, said trigger adapted to engage the locking plate and adapted to be engaged and released from
